(57) **CLAIM**

The ornamental design for molded plastic container, as shown and described.

DESCRIPTION

FIG. 1 is a perspective view of a molded plastic container constituting my invention;

FIG. 2 is a side view of FIG. 1;

FIG. 3 is another side view of FIG. 1;

FIG. 4 is a bottom view FIG. 1; and,

FIG. 5 is a top view of FIG. 1.

The broken line showing of a handle is for illustrative purposes only and forms no part of the claimed design.
